TOY ROUNDABOUT

William H. J. Downey, Wilmington, Del.

Application December 9, 1947, Serial No. 790,645

2 Claims. (Cl. 272—31)

1

My invention relates to toys and more particularly to that type of toys in which a standard supports a pair of diametrically oppositely extending arms so that said arms are set into rotary motion about said standard by their own gravity.

An object of my invention is to provide a toy of the character indicated above, the standard of which consists of a flat steel bar twisted about its longitudinal axis to form a spiral guide way for the radial arms, which consist of a continuous piece of wire having in its longitudinal center a loop formed to correspond with the pitch of the spiral of the twisted standard.

Another object of my invention is to provide a toy of the character indicated above, on the ends of the radial arms of which toys in the shape of aeroplanes or the like are suspended so that they are adapted to swing freely on said arms.

A further object of my invention is to provide a toy of the character indicated above, the standard of which is secured with its lower end on the upper end of a support resting on removable legs, so that the standard extends substantially vertical in upward direction.

A further object of my invention is to provide a toy of the character indicated above, having on its upper end a removable ornamental member.

A further object of my invention is to provide a toy of the character indicated above the upper end portion of the standard support of which is such that the loop of the horizontal radial arms may encircle said end portion and permit the rotary movement of said arms to continue until the impulse caused by the gravity of the arms is exhausted.

A further object of my invention is to provide a toy of the character indicated, in which the upper end portion of the twisted standard is undercut so that it maintains the twisted shape of the standard and is adapted to enter into the lower end of a rectangular sleeve twisted at the same pitch as the standard and having the same outside dimensions as the standard, thereby forming a smooth continuation thereof and permitting a similar under-cut end of a similarly twisted bar to enter the upper end of the sleeve to form a further continuation of the standard.

Other objects of my invention not specifically mentioned may appear in the following specification describing my invention with reference to the accompanying drawing illustrating a preferred embodiment of my invention. It is, however, to be understood that my invention is not to be limited or restricted to the exact construction and combination of parts described in

2

the specification and shown in the drawing, but that such changes and modifications can be made which fall within the scope of the claims appended hereto.

5 In the several figures of the drawing, similar parts are designated by similar reference characters and

Figure 1 is a view in perspective of a toy constructed in accordance with an embodiment of 10 the invention;

Figure 2 is an enlarged fragmentary view in elevation showing the coaction between the loop and standard;

Figure 3 is a view similar to Figure 2 but 15 showing the loop at its lowermost position;

Figure 4 is a fragmentary view in perspective of the loop and associated arms as herein comprised;

Figure 5 is an enlarged vertical sectional view 20 taken through one of the aeroplanes herein embodied;

Figure 6 is a sectional view taken substantially on the line 6—6 of Figure 5;

Figure 7 is a sectional view taken substantially 25 on the line 7—7 of Figure 6;

Figure 8 is a view in plan of the blank from which the combination rudder and elevator is produced;

Figure 9 is a sectional view taken substantially 30 on the line 9—9 of Figure 5;

Figure 10 is a detail sectional view taken substantially on the line 10—10 of Figure 5;

Figure 11 is a fragmentary elevational view of a modified form of standard, and

35 Figure 12 is a sectional view taken substantially on the line 12—12 of Figure 11.

The toy forming the subject matter of my invention comprises a standard 15 which is preferably made from a flat bar twisted about its longitudinal axis in such a manner as to form a spiral thread 15a of short pitch and of constant diameter throughout its entire length which provides a corresponding spiral groove or guide 15b. The lower end portion of the standard 15 is secured to a support 16 in any suitable conventional manner depending on the material from which the support is made. The uppermost end portion 17 of the support 16 is shaped into an upwardly extending round stub rod of the same diameter as the twisted standard 15 for a purpose to be described later. The lowermost portion 18 of the support 16 is preferably shaped into a downwardly pointing cone and a plurality of 45 legs 19, preferably three, carry this support and

50 55 legs 19, preferably three, carry this support and

the standard thereon and extend slantingly downwardly and outwardly from the support portion 18. The upper end portions of the legs 19 are inserted into holes 20 extending into the conic support portion 18 at an upwardly slanting angle. To make sure that the low portions of legs 19 are of equal length, a stop ring 21 is shrunk on or otherwise secured to each leg at the desired distance from the bottom end thereof. The upper end portion 22 of the standard 15 is under-cut or reduced in size but is twisted at a corresponding angle to the main portion of the standard.

A pair of arms A substantially in longitudinal alignment is formed preferably from a continuous piece of wire, the center portion of which is shaped to form an open loop 23 which is shaped to define a spiral having the same pitch as the spiral guide way formed by the twisted standard 15. One end of the loop joins an end of one arm in a rounded knee 23a and the other end of the loop joins the other arm in a correspondingly formed rounded knee 23b. The knees are in different planes as will be readily apparent, so that when the loop is in place around the standard, a part of the loop will lie in the spiral groove 15b with one knee resting upon the edge of the spiral thread as, for example, the knee 23a, while the other knee will engage in the guide way and have contact with adjacent edges of two convolutions of the spiral thread. The arms A extend in opposite directions relative to each other, and the end portion of each arm is formed into an open hook 24 for a purpose to be described later.

A comparatively short support rod 25 has on its upper end an eye 26 adapted to engage one of the open eyes 24. There are two support rods 25 and on the lower end of each of these rods an open hook 27 is formed to engage and supports a flying toy T, for instance an aeroplane. The two aeroplanes T may represent different models of such apparatus. One may be provided with a single propeller 28 and the other with three or any other desired number of propellers.

When the toy is to be used the aeroplanes T are hung on the hook ends 24 of the arms A, which then are put onto the upper end of the standard 15, by inserting said standard through the loop 23 of the arms A, so that the loop engages the convolutions of the twisted spiral, and the weight of the arms and of the aeroplane hanging thereon urges the loop to slide downwardly on the standard. The engagement between the loop and the convolutions of the standard imparts to the radially extending arms a rotary movement about the vertical axis of the standard, and the centrifugal force urges the aeroplanes to swing outwardly from the arm ends 24, giving the impression of aeroplanes banking during flying through a curve. When the arms arrive at the bottom end of the standard 15, the loop 23 slides onto the top end portion 17 of the support 16 and the rotary movement of the arms and the object hanging thereon will continue until the impulse given to the arms by their gravity and by the centrifugal force of said objects will be exhausted.

An ornamental top member 29 is mounted removably on the under-cut top end portion 22 of the standard 15 which enters a twisted slot 30 provided in the bottom portion of said ornamental member. When it is desired to prolong the standard 15, a rectangular sleeve 31, which is twisted at the same pitch as the standard, and has the same outside dimensions as said standard

and inside dimensions, which are a little larger than the under-cut top portion 22 of the standard, are mounted on the standard by sliding the under-cut top portion of the latter into the sleeve 31 after removing the ornamental top member 29. A prolongation member 32 is made from a bar similar to the one from which the standard 15 is made, and this bar is twisted at the same pitch as the standard. The lower end portion 33 of the prolongation member is under-cut in the same manner as the upper end portion 22 of the standard 15, and fits slidingly into the sleeve 31. The upper end portion (not shown) of the prolongation member 32 may be under-cut and twisted like the upper end portion 22 of the standard 15, so that it is adapted to enter the slot in the bottom of the ornamental member 29 or a second prolongation sleeve 31.

Each aeroplane T comprises a body B formed by a curved top portion 34 and a substantially flat bottom 35. The curved top portion 34 has an arcuate intermediate portion 36, which tapers off forwardly and rearwardly as shown at 37 and 38 respectively in Figures 5, 6 and 9. In the bottom 35, a plurality of longitudinal narrow slots 39 is provided adjacent to its longitudinal edges and the curved top portion 34 has a corresponding number of ears or lugs 40 formed on its edges and adapted to be inserted through the slots 39 and to be bent over to lie flatly underneath the bottom 35, the middle portion 41 of which extends parallel to the uppermost longitudinal portion of the curved top 34. The forward portion 42 of the bottom slants forwardly and upwardly as shown in Figures 5 and 6 and the rear bottom portion 43 slants rearwardly and upwardly as shown in Figures 5 and 9. In the front end portion of the above described body B of the aeroplane T, a plug 44 is inserted fitting the inner contour of said body portion and secured in place by indentations 45 made in the front top portion 37 and the front bottom portion 42 by means of an appropriate tool (not shown) and engaging said plug. The front part 46 of the plug 44 extends forwardly beyond the body B and is of reduced cross section relative to the plug portion located inside of the body. The front surface of the plug 44 is protected by a sheet metal plate 47, and the propeller 28, of any conventional shape and construction, is rotatably mounted on said plug by means of a nail 48 or the like extending through the hub 49 of the propeller 28 and the protection sheet 47 and entering the plug 44. On each side of the intermediate bottom portion 41, a vertically downwardly extending bracket 50 is formed. An axle 51 is rotatably mounted in these two brackets and adjacent each end of said axle a wheel 52 is mounted. Inside the intermediate body top portion 36 a horizontal transverse plate 53 is arranged, which is provided at each of its ends with two lugs 54 extending through horizontal slots 55 provided in the side portions of the arcuate intermediate body portion 36. In the upper curved part of this body portion located above the bench formed by the plate 53, an oval opening 56 is arranged. Adjacent the foremost portion of this opening a transverse slot 57 is provided in the forward top body portion 37 adapted to receive a lug 58 formed on an imitation steering wheel 59 stamped out of sheet metal or the like. The lug 58 extends through the transverse slot 57 and is bent over to lie flatly against and engage the body B to secure the steering wheel 59.

A human figure 60 is formed in a well known manner from two sheet metal halves to impart to said figure a sitting posture. The hands 61 of said figure are placed in position to grip the steering wheel 59, and two tongues or lugs 62 formed on the lower part of the body of the figure 60 extend through two slots 63 provided in the bench 53, so that the human figure 60 may be placed in working position on said bench or may be removed therefrom. Rearwardly of the cockpit opening 56 in the body B and symmetrically to the vertical center plane of the body a hole 64 is arranged, which is adapted to be engaged by the open hook 27 on the lower end of the short support rod 25, so that the aeroplane T may be removably suspended on the end of one of the arms A.

A tail skid 65 is formed from a piece of wire and is secured in the following manner onto the body B under the tail part 43. Rearwardly of the intermediate bottom portion 41 and symmetrically to the vertical center plane of the body B, two holes 66 and 67 respectively, are provided in the rear bottom portion 43 at a distance behind each other. On the front end of the tail skid 65, an upwardly and forwardly extending angular portion 68 is formed, and on the rear end of said skid the wire forming the skid is bent upwardly as at 69 and the upper end of this wire portion is bent rearwardly as at 70, so that the tail skid may be secured by inserting the upward and rearward extending wire portions through the rear hole 67 and then inserting the angular front wire portion 68 through the forward hole 66.

The rear end of the aeroplane body B is open and a combination rudder and elevator R is mounted oscillatingly in said rear end and extends rearwardly from said body. The combination of rudder and imitation elevator R is preferably made from a sheet metal blank. This blank consists of one piece of sheet metal having two wing portions 71 and 72 respectively having each a rear edge 73 and 74 respectively, which run at an angle of approximately 120° to each other. A bend line 75, running forwardly from the apex of the angle formed by the rear edges 73 and 74, divides this angle into halves and the apexes of these two halves are rounded off as shown at 76 in Figure 8. From the outer end of the rear edge 74 of the wing portion 72, a side edge 77 extends toward the bend line 75 at an angle of approximately forty-five degrees to the rear edge 74 and the apex of this angle is rounded off, as shown at 78 in Figure 8. A second bend line 79 is indicated in Figure 8 to extend from the approximate center of the rear edge 74 forwardly at an angle of about one hundred degrees to the inner half of said edge, and the side edge 77 stops at its intersection with the second bend line 79. A short edge 80 forming a continuation of the second bend line extends somewhat beyond the intersection point of said line with the side edge 77 and another edge 81 of the blank extends at right angles to the short edge 80 toward the first bend line and ends on the intersection with this line, from where another blank edge 82 extends forwardly in the same direction with the first bend line 75. The wing portion 71 is shaped exactly like the wing portion 72 and a bend line is indicated in the drawing and is located in the wing portion 71 like the bend line 79 in the wing portion 72, so that the wing portion 71 has a side edge corresponding to the side edge 77, and short forward extending edge 85 corresponding to the short edge 80. From the outer end of the short

edge 85, a still shorter edge 86 extends outwardly at a right angle to the edge 85 and a side edge 87 extends forwardly to the short edge 86. A front edge 88 extends at a right angle to the side edge 87 inwardly from said side edge until it crosses or meets the edge 82. The combination R of rudder and imitation elevator is made from the above described blank in the following manner: First the blank is bent on the bend lines 79 and 83 so that the outer portions 72a and 71a of the wing portions extend at right angles to the main wing portions, and then the blank is folded along the bend line 75 until the two main wing portions extend alongside of each other and the two outer wing portions extend in opposite directions to each other at right angles to the folded main wing portions. The blank portion defined by the edges 86, 87, 88 and 82 is then rolled to form a hinge sleeve 89 adapted to be inserted into the open rear end of the body B. A rudder pin 90 extends centrally and vertically through the body top portions 38 and 43 adjacent to the rear ends thereof and through the hinge sleeve 89. It is secured in position by two rivet heads 91 and 92 respectively and supports the rudder and elevator unit pivotally on the aeroplane body.

In each side of the intermediate top body portion 36, a longitudinal horizontal slot 93 is provided. Two wings 94 are provided and the inner end portion 95 of each wing is bent upwardly at right angles to the main wing portion. By inserting the inner ends 95 through the slots 93 into the body B and then pivoting the main wing portions downwardly until the inner wing edge portions engage the sides of the body, the wings are removably secured to said body. When it is desired to equip one or both aeroplanes of my toy with more than one propeller, imitation motor housings 96 are secured onto the wings 94 in any desired conventional manner at the front edges of the wings and to forward end of each motor housing a propeller 28 is rotatably secured in the manner described above for an aeroplane equipped with a single propeller.

I claim:

1. In a toy of the character set forth, a standard formed to provide a continuous thread spiral of constant diameter throughout the length of the standard, the threads being closely formed to provide a short pitch, and a toy suspending unit comprising a pair of arms substantially in longitudinal alignment and a joining portion between the arms, said joining portion comprising an open spiral loop disposed to one side of the substantially aligned arms and encircling the standard and lying in part in the space between two adjacent thread convolutions, one end of the loop being arranged to ride on the edge of the thread and the other end of the loop being arranged to run in the space between the said adjacent convolutions of the thread, the outer ends of the arms being designed to support freely suspended swinging toys.
2. A toy of the character described in claim 1, including a supporting base for the standard having an upwardly extending cylindrical portion of the same diameter as the standard and adapted to enter the loop to provide a smooth pivot around which the loop and arms may freely turn.

WILLIAM H. J. DOWNEY.
